UNITED STATES PATENT OFFICE.

WILLIAM F. COOPER, OF NORWALK, OHIO, ASSIGNOR OF ONE-HALF TO
THE A. B. CHASE CO., OF NORWALK, OHIO, A CORPORATION OF OHIO.

MECHANICAL MUSICAL INSTRUMENT.

No. 833,026.

Specification of Letters Patent.

Patented Oct. 9, 1906.

Application filed May 29, 1905. Serial No. 262,876.

To all whom it may concern:

Be it known that I, WILLIAM F. COOPER, a citizen of the United States of America, residing at Norwalk, in the county of Huron and State of Ohio, have invented certain new and useful Improvements in Mechanical Musical Instruments, of which the following is a specification, reference being had therein to the accompanying drawings.

This invention has relation to mechanical musical instruments, and relates in particular to that class of instruments in which the hammers are caused to strike the strings by the automatic operation of pneumatic mechanism controlled and governed by a traveling sheet of perforated paper. In most instruments of this class the pneumatically-operated mechanism and the perforated sheet of paper and devices for causing the same to travel so as to effect and control the operation of the pneumatically-operated mechanism are contained in a comparatively large case that is located adjacent a piano or similar keyed instrument in front of the keyboard, certain keys constituting component parts of the pneumatically-operated mechanism projecting over the keys of the keyed instrument and depressing the same in such order and manner as to effect the playing of the desired composition. The particular keys operate successively or in groups, being dependent upon the location and arrangement of the perforations in the traveling sheet of paper. Apparatus of the above character is expensive, cumbersome, and unsightly, and its position in front of and over the keyboard of the instrument to which it is applied prevents the playing of the instrument in the ordinary manner until it has been removed.

It is the object of my invention to produce an apparatus of novel form and construction which can be applied to and removed from keyed instruments of ordinary construction, such as upright pianos and the like, without alteration of the instrument or its casing in any noticeable manner and which will not detract from the appearance of the instrument to which it is applied or in any manner interfere with or render difficult the task of playing the instrument in the ordinary manner by those possessed of the requisite skill.

In carrying my invention into effect I so construct and arrange the tracker-box,

which is that part of the device that contains the mechanism for causing the perforated sheet of paper to travel over the terminals of ducts leading to the pneumatically-operated mechanism, that it can be readily arranged in operative position in front of the keyboard of an instrument to be played mechanically, and when desired it can be swung under the keyboard and out of the way and out of sight, so that the instrument can be played upon in the ordinary manner. All the other appliances and mechanisms of my improved apparatus are, with the exception of a pair of operating-pedals and certain appurtenances thereof, arranged within the casing of the instrument and completely concealed from view, and the pedals above referred to are so constructed that they, too, can be folded up against the lower front board of the piano and so covered and concealed as to be unobservable.

Other objects and improvements will be presently developed; and my invention consists in the novel construction, combination, and arrangement of parts hereinafter described, and briefly set forth in the claims.

I have illustrated my improvements in the accompanying drawings, wherein like numbers and letters of reference designate corresponding parts in the several figures, and in which:

Fig. 1 is a fragmentary perspective view of the lower portion of an upright piano with my improvements applied, the lower front board being removed and the mechanical playing apparatus swung around so as to afford a view of the rear portions of the same. Fig. 2 is a perspective view of the same with the tracker-box swung down to its inoperative position and with the pedals folded up. Fig. 3 is a similar view to Fig. 2, but with the tracker-box raised to its operative position and the pedals turned down to their operative position. Fig. 4 is a perspective view showing the lower part of an upright piano-forte with my improvements applied and in position for operation, the lower front board of the piano being removed. Fig. 5 is a top plan view, on an enlarged scale, of the tracker-box, its supporting devices, and appurtenant parts, a portion of the covering being removed to show the contained mechanism. Fig. 6 is a top plan view, on another enlarged scale, of the entire apparatus.

detached from the piano. Fig. 7 is a front elevation of the same, on a slightly-larger scale than Fig. 6, the tracker-box and pedals being omitted. Fig. 8 is an end elevation of the same, on the same scale as Fig. 7, the motor-apparatus being removed. Fig. 9 is a sectional view on the line $x-x$ of Fig. 5. Fig. 10 is a detail sectional view on the line $y-y$ of Fig. 5. Fig. 11 is a vertical sectional view, on an enlarged scale, through the center of the motor-pressure regulator. Fig. 12 is a front elevation, on an enlarged scale, of the controller-box with the cover thereof removed. Fig. 13 is a vertical sectional view of the controller-box on the line $x-x$ of Fig. 12 with the cover in position and looking in the direction indicated by the arrow. Fig. 14 is a sectional view on the line $y-y$ of Fig. 12 also looking in the direction of the arrow. Fig. 15 is a detail side elevation, partly in section, of the pedals, showing their connection with the main bellows. Fig. 16 is a top plan view of the pedals. Fig. 17 is a vertical transverse sectional view through one of the expression-controllers. Fig. 18 is a front elevation of a portion of the expression-controller board and the expression-controllers, the top of one of the latter being removed. Fig. 19 is a detail plan view of part of the expression-bellows; and Fig. 20 is an end elevation of the playing mechanism, showing the tracker-box in its raised position thereon in full lines and in its lowered position in dotted lines.

35 In the following specific description letters of reference will be employed to designate parts or groups of mechanisms which may be described by general terms and reference-numerals to designate individual parts.

40 *The general arrangement.*—The entire apparatus, with the exception of the tracker-box, the pedal devices, and certain levers by means of which the operation is governed and controlled, is arranged in the piano A within the lower front board B and is supported by two end frames 1 and 2, that are connected together by certain component parts of the mechanism and by a metallic bar 3, that terminates in a hinge member 4, a second metallic bar 5 being carried at one side near the bottom and this bar terminating in a hinge member 6. The hinge members 4 and 6 are attached by removable pintles 7 to hinge members suitably arranged within the piano-case and attached to the same. Two metallic bars 8 extend upwardly from the bar 3 and then outwardly beneath the keyboard of the piano, and these bars serve as supports for the tracker-box C. The main bellows are designated D D, and these bellows, as well as the main-bellows reservoir E, are attached to the bellows foundation-board 9. Adjacent the main-bellows reservoir is located the motor-pressure regulator F; and alongside the latter is arranged the controller-

box G, the regulator F and box G being attached to the bellows foundation-board 9 and both being in communication with reservoir E through a channel 10 in the foundation-board 9.

Above the controller-box G are the two expression-controllers H I, these controllers being carried by an expression-controller board 11, which is formed with certain internal channels and ports that are in communication with the controller-box G by a conduit 12 and also in communication with the expression-controllers H I and with the channels and ports of the pneumatic-action mechanism of the primary board J and its connected parts.

The controller-box G is connected by a conduit 13 with a motor K, and a motor-shaft 15 extends from the motor under the bars 8 and carries one sprocket-wheel 16 on its end, 85 from which motion is communicated by a chain to the mechanism of the tracker-box C.

A pivoted tempo-lever 17 is arranged at one side of the tracker-box and carries a pointer 18, that indicates on a suitably-inscribed bar 19 the tempo of the composition being played. Three other levers (designated, respectively, 20 21 22) are pivoted on a bar 23, projecting from the left-hand side of the tracker-box, these being the sustaining and expression levers, by means of which the expression, phrasing, or shading of the composition being played is effected.

The tempo-lever 17 is connected by a rod 24, a bell-crank 25, a rod 26, and a crank 27 with a rock-shaft 28, that extends through the controller-box G, and by the movement of which rock-shaft the mechanism within the controller-box is operated. The sustaining-lever 22 is connected by a horizontal rock-shaft 29, that has a crank-arm on each end, to a vertical rod 30, which is in turn connected to a pivotal lever 31, that engages the rod 32 of the sustaining-pedal of the piano. The expression-levers 20 and 21 are connected, respectively, to rock-shafts 33 34, that have cranked ends and are connected to vertical rods 33' 34', that communicate motion to a pair of rock-shafts 35 36, that have downwardly-depending spring-arms 35' 36', that bear, respectively, on the movable bellows-boards of the expression-controllers H I. Motion is also imparted by the rods 33' 34' to a second set of rock-shafts 37 38, that extend into the expression-controllers H I and operate the mechanism contained within the same.

The pedal mechanism is designated L and is arranged in front of and at the lower edge of the front board of the piano, the construction and arrangement of the parts of this mechanism being such that the entire structure may be folded up against and partly into the front board when not in use, so as to be concealed from sight and out of

the way of a performer when playing the piano in the usual manner.

The tracker-box C is connected by ducts 39 with the primary board J.

Having thus described the general arrangements of parts, I will now proceed to describe under appropriate headings the several parts in detail.

The pedal mechanism.—The lower front board B of the piano A is formed with a recess 40, and at the lower edge of this recess a board or frame 41 is hinged to bars 41', which are carried by the base-board of the main bellows D, and which bars extend through an opening at the bottom of the front board B, and upon this board or frame are arranged two hinged pedals 42 42, which are connected by jointed levers 43 43 with the main bellows D D. The pedals 42 42 each carry a lug 43' at its inner edge, and these lugs engage, when both pedals are depressed simultaneously, with the inclined ends of arms 44, carried by a rocking and sliding plate 45, that is pivotally attached to a curved spring 46, mounted on the board or frame 41. When, however, the pedals are separately or alternately depressed, the plate 45 rocks or swings on its pivotal point, when one of the lugs strikes one of the inclined ends of one of the arms 44, and thus throws the arm backwardly and out of position for engagement with the lug.

Both pedals are depressed simultaneously and engaged, as above described, when it is desired to fold the pedal board or frame up against the front board B, and when so folded up the board or frame is held in position by a latch 47, and as the board is folded up the curved portion of spring 46 strikes the bottom of the recess 40 and being straightened out forces the plate 45 upwardly, which motion disengages the lugs 43 of both pedals from the arms 44 and frees the pedals, so that when the board or frame is again lowered the pedals will assume their proper working position.

The tracker-box.—The tracker-box C carries two brackets 48 48, that are pivotally attached at 49 49 to fastenings 53 53, carried by the bars 8 8, and the brackets each carry a latch-block 50, which when the tracker-box is elevated is engaged by a triangular head 51, carried by a strong spring 52, mounted on the side of the casting 53, attached to bars 8 by screws 54 54.

The tracker-box is composed of heads 55 56, a partition 57, and a suitable inclosing covering or casing 58 and contains a paper-roll 59, a take-up roll 60, and a tracker-bar 61, the latter being formed with openings equal in number to the keys of the piano and being connected by ducts 62 with a movable jointing-bar 63, that is carried by the brackets and that has openings corresponding in number to the ducts 62, the openings in this

jointing-bar registering when the tracker-box is in its elevated position, with similar openings in a stationary jointing-bar 64, carried by castings 53, and the latter jointing-bar being connected by the ducts 39 with the primary board J.

The shaft 65 of the take-up roll 60 carries a gear-wheel 66, and a loose sprocket-wheel 67 is mounted on a longitudinally-movable shaft 68 and carries a clutch member 69, 75 adapted to engage a clutch member 70, that is carried by a sprocket-wheel 71, fixed on the longitudinally-movable shaft 68. The shaft 68 carries on its inner end a pinion 72, that at one position of the shaft meshes with the gear-wheel 66. The clutch member 70 is formed with a groove 73, that is embraced by the bifurcated ends of a pivoted lever 74, which has a laterally-extending curved arm 75, that is struck by a pin 76 on the tempo- lever 17 when the lever is moved inwardly to the point marked "Rewind" on the bar 19, the movement of the lever 74 produced thereby bringing the clutch members 69 and 70 into mesh and throwing the pinion 72 out 90 of mesh with the gear-wheel 66. A chain 77 connects the sprocket-wheel 71 with the sprocket-wheel 16 on the motor-shaft 15, and a chain 78 connects the sprocket-wheel 67 with a sprocket-wheel 79, that is fixed on a 95 clutch-shaft 80, connected to the shaft 81 of the paper-roll. By this construction and arrangement of parts the take-up roll will be driven positively in one direction when the clutch members 69 and 70 are out of mesh, 100 and the paper-roll will be driven positively in an opposite direction when the clutch members 69 and 70 are in mesh with one another.

A sheet of suitably-perforated paper is wound from the paper-roll around the take-up roll and in its movement passes over the tracker-bar, admitting air to the openings therein accordingly as the perforations in the paper are brought into register with the openings in the tracker-bar.

The expression-levers 20 and 21 and the sustaining-lever 22 are, as before described, pivotally mounted on the arm 23, and the rods 20', 21', and 22', by which these levers are connected to the rock-shafts 29 33 34, are connected to an arm 29', that projects from the bar 8 in rear of arm 23 by spiral springs 82, which are attached at one end to said arm 29' and at the other to blocks 83, carried by said rods 20', 21', and 22', which blocks also serve as stops to limit the inward movement of the rods 20' 21' 22'.

The rods 20', 21', and 22' are pivoted to their respective levers 20, 21, and 22 in alignment with the pivots 49 49 of the tracker-box brackets, so that when the tracker-box is swung downwardly the arm 23 and the said levers can swing downwardly also.

The expression-controller.—Referring to Fig. 17 of the drawings, which is a vertical

sectional view taken through the board 11 and one of the expression-controllers, the expression-controller H being the one shown in section in this view, it will be observed that 5 the board 11 is provided with an upper channel 84 and a lower vertical channel 85, the channel 84 leading to the primary board and the channel 85 being in communication with the conduit 12, leading to the controller-box. 10 The expression-controller is in the form of a small bellows that is composed of a rectangular open frame 86, a movable bellows-board 87, hinged to the frame 86 at 88, and a flexible air-proof integument 89, that forms the 15 sides and one end of the bellows structure, which with its appurtenant parts constitutes one of the expression-controllers. The frame 86 has at one side an inwardly-projecting bar 90, and to this bar is attached a flap 91, of flexible material, that is attached at its other end to a block 92, mounted on the inside of the bellows-board 87, this flap being designed to control a port 93, leading from the channel 85 to within the controller. The 20 bellows-board 87 carries a small plate 94, that projects laterally beyond the side of the bellows-board, and a spring 95 is arranged alongside the expression-controller H, the free end of the spring extending under the plate 94 25 and the spring tending to press the bellows-board 87 outwardly to the position shown in Fig. 17. Alongside the port 93 a second port 96 is provided, this port also affording communication between the channel 85 and the 30 inside of the controller H, and over this port 96 is arranged a flap-valve 97, that is pivoted to a bar 98, fastened to expression bellows-board 87. A small spring 99 is connected at one end to the valve 97 and at the other end 35 to the bar 98, and this spring tends to maintain the valve 97 in open position—that is, raised relatively to the port. The rock-shaft 37 passes through a groove 100 in the board 11, and this rock-shaft is provided with a 40 downwardly-extending end 101, that is attached to the valve 97 by means of an eye 102, and the rock-shaft 37 extends through the frame 1 and has an arm 103 on its outer end that bears upon the top of a block 104, 45 that is adjustably mounted on the rod 33, said block being held in adjusted position by a screw 105. The parts above described as appertaining to the expression-controller H are all repeated in expression-controller I, 50 the two controllers being identical in construction and provided with the same appurtenant parts. The expression-controller H controls that portion of the scale of the instrument that contains the bass notes, and the 55 channel 84 is in communication with the interior of the controller H by a port 106, this channel leading to that portion of the channel of the primary board that is connected to the pneumatics which operate the hammers of the 60 bass strings of the instrument, while a simi-

lar channel 107, that communicates by a port 108 with the expression-controller I, leads to that portion of the channel of the primary board which is connected to the pneumatics which operate the hammers of the treble 70 strings of the instrument. The channel 85 in the lower portion of the board 11 is in communication with expression-controller I by two ports 109 and 110, similar to the ports 93 and 96, that lead from the channel 85 into 75 the controller H. The main channel of the primary board 11 is divided into two sections, one appertaining to the bass pneumatics and the other to the treble pneumatics, this partition being designated 11' and shown in dotted lines in Fig. 7 of the drawings. 80

The operation of the expression-controllers is as follows: The main bellows D D, being actuated will create a partial vacuum in the main reservoir E, and, the air being exhausted from the motor-bellows through the conduit 13 and the controller-box G, the port 10, and the motor-pressure regulator F, the motor-bellows will be set in motion and will impart motion to the motor-shaft 15, through 90 which and the sprocket-wheel 16 motion will be communicated to the tracker-box mechanism. The perforated sheet of paper in the tracker-box mechanism in passing over the tracker-bar will admit air through the perforations in the paper into the duct 39, and this admission of air to the several ducts will of course depend upon the positions of the perforations in the paper. The pneumatics by means of which the hammers are operated 100 are caused to collapse, and thus actuate the hammers by reason of the abstraction of air from the pneumatics by the suction created by the main bellows, and this action takes place as soon as the air has been admitted 105 through the ducts 39 by the movement of the paper in the manner above described. This action of the tracker-box and the pneumatics is old and well known, and I have only referred to it in order to render clear 110 the function and mode of operation of my improvements. It being understood that the pneumatics are operated by the extraction of air therefrom, it will be readily understood that the amount of air abstracted 115 in a given time will determine the force with which the pneumatics will operate. Thus, for instance, if all the air is abstracted very suddenly from a pneumatic the latter will collapse suddenly and with a very great 120 force, whereas if a less quantity than the maximum quantity of air is abstracted from the pneumatics by the main bellows in the same period of time the pneumatic will collapse without an appreciable difference in 125 the time consumed in the operation, but with less force, and the hammer will therefore strike the strings a softer blow than in the first instance. The abstraction of air from the pneumatics necessarily involves a 130

flow of air through the primary-board channel, through the channels of the expression-controller board, and through the expression-controllers H and I. The tendency of the 5 springs 95 of the controllers H and I is to maintain the bellows-board 87 at its maximum forward position, and in this position the flap 91 stands at a considerable distance from the port 93, and therefore the passage 10 through this port is unobstructed and the maximum amount of force is imparted to the motion of the pneumatics. In the normal position of the parts the spring-arm 35' is out of contact with the plate 45 on the bellows-board, and the first movement of the expression-lever has the effect of closing the valve 97, this closing being effected gradually or rapidly at the will of the operator. A further movement of the expression-lever 15 brings the arm 35' into contact with the plate 45', and thereafter the further movement of the expression-lever will cause this spring-arm to bear with increasing strength against the plate on the bellows-board, and, 20 this action being opposed to the resilient action of the spring 95, the atmospheric pressure upon the bellows-board will gradually increase in power according as the spring-arm 95 is pressed with increasing force 25 against the bellows-board, and the bellows-board will therefore swing inwardly and bring the flap 91 gradually close to port 93, which action will have the effect of throttling the suction, and thereby decreasing the force 30 which will be exerted by the pneumatics when they are thrown into operation to cause the hammers to strike the strings. A reverse movement of the expression-lever will of course result in a reversal of the action 35 of the parts, and the reverse movement of the expression-lever is effected by means of a suitable retracting-spring 82, connected to rod 20' and the arm. 40

The controller-box.—The motor-controller box G (see Figs. 12, 13, 14) is attached in any suitable manner to the bellows foundation-board 9 and is of rectangular form in outline and of somewhat greater depth at its upper end than at its lower end and is provided with 45 a removable top or cover 111. The box G is divided centrally by a partition 112 into two compartments 113 and 114. Two ports (designated, respectively, 115 and 116) are formed in the back of compartment 113, the 50 port 115 opening into a channel 117, that leads to the motor-pressure regulator F, and the port 116, opening into the channel 10, that leads directly to the main reservoir E. A plate 119, which is formed with a long tapering slot 120, is fixed over the port 115, and guide-strips 121, 121 are arranged at the sides of the plate 119, the strips serving to guide a sliding valve 122 and maintain it in close contact with the plate. The valve 122 has a 55 lug 123 on its outer side, and to this lug is

pivotedly attached a rod 124, which is pivotally attached at its other end to a crank 125, fixed on the rock-shaft 28. The port 116 is normally closed by a valve 126, that is hinged by means of a strip of flexible material 127, 70 which forms the face of the valve and extends below the same and is fastened at its edge by a block 128. An angularly-disposed arm 129 is attached to the valve 126 and extends within the range of motion of the crank 125 75 and is struck by that crank, so as to lift the valve 126 from its seat at a certain position of the crank, a spring 130 normally holding the valve to its seat. The conduit 13, leading from the motor K, opens into the compartment 113, and the air drawn from the motor passes through the compartment 113 to the main bellows through the port 115 or the port 116, or both, accordingly as one or both of the valves 122, 126 are opened. 80

When the rock-shaft 28 is rocked by the movement of the tempo-lever 17, the slot 120 is opened more or less, according to the amount of movement of the tempo-lever, and consequently a greater or less amount of 90 air is drawn in a given time from the motor, and the motor will thereby be caused to operate more or less rapidly.

The compartment 114 of the box G contains a valve 131, that has a facing 132 of 95 suitable flexible material, this facing constituting also a hinge for the valve and being fastened at 133 to the back of the compartment. The valve 131 is arranged in front of a port 134, which opens into the channel 10, and the valve carries an arm 135, that is loosely secured on the valve by a screw 136, that is not screwed down quite tight, so that the arm has a slight movement independently of the valve. A spiral spring 137 is attached to the arm 135 at one end and at the other end to the upper end of the box. A crank-arm 138 is carried by the rock-shaft 28, this crank-arm being so positioned on the shaft that when the shaft is rocked to such an extent as to cause the crank 125 to contact with the arm 129 of the valve 126 the crank-arm 138 will simultaneously contact with the arm 135, so that at the extreme position of the rock-shaft the valve 126 will be opened 100 and the valve 131 will be closed. The conduit 12 opens into compartment 114, and therefore when valve 131 is closed the suction of the main bellows will no longer affect the action mechanism of the instrument. At 110 this time, as the valves 122 and 126 are opened to their fullest extent and the tempo-lever being at the rewinding position, the full power of the main bellows will be exerted in operating the motor alone and the motor will 115 be caused to run at great speed, so as to rewind the perforated sheet of paper very rapidly upon the paper-roll.

The motor.—This portion of the apparatus is of old and well-known form and need not 120

be particularly described. It is sufficient to say that it consists of a plurality of bellows 171, each of which is fitted with a slide-valve 172, the slide-valves being connected to the 5 cranks of motor-shaft 15, so that as the crank revolves air will be alternately admitted and cut off from the separate bellows of the motor, and these being caused to collapse by the exhaustion of air through conduit 13 and expanded by suitable springs the motor-shaft will be caused to revolve constantly in the one direction.

The motor-pressure regulator.—The motor-pressure regulator F is in the form of a bellows, and the movable board 173 thereof carries a loosely-suspended strip 174 of flexible material, that is adapted to more or less close a port 175, that leads into the channel 10. The channel 117 leads into the interior of the 20 regulator F, and the function of the regulator is to maintain an equal pressure in the suction between the main reservoir and the pneumatic-action and the motor. This is accomplished by the movement of the movable board 173, which moves with each variation of the suction, and by the strip 174, which more or less throttles the port 175, according to the position of the movable board 173.

Operation.—The operation of each of the 30 groups of mechanisms has been described in the course of the specific description of the same, and consequently it is only necessary to briefly describe the conjoint action of all. The pedals being worked by the feet will 35 work the main bellows, and this will create a partial vacuum in the main reservoir. Air will be then exhausted from the motor and from the pneumatics, and the sheet of paper in the tracker-box being put in motion air 40 will be successively admitted to the primary-board borings, so as to operate the proper pneumatics, and thus play the notes called for by the particular music-sheet in the tracker-box. The shading or phrasing effects are produced by the manipulation of the 45 levers 20, 21, and 22 in the manner hereinbefore described, and the tempo of the composition is controlled by the movement to one side or the other of the tempo-lever. When 50 the music-sheet has been entirely unrolled from the paper-roll and onto the take-up roll, the tempo-lever is moved in toward the end of the tracker-box, and by the mechanism hereinbefore described the action of the 55 paper-roll and the take-up roll are reversed and the music-sheet will be rerolled on the paper-roll, the suction during this winding being cut off from the pneumatic action and exerted wholly upon the motor by the operation of the valves in the controller-box in the manner hereinbefore fully described.

Having described my invention, I claim—

1. In a mechanical musical instrument, the combination of a piano, pneumatically-operated mechanism contained within the case

of the piano, below the level of the keyboard and detachably attached to the piano-case and a tracker-box carried by said mechanism and arranged exterior of the case.

2. The combination with a keyed instrument, of a mechanical playing attachment movably attached to the case of the instrument and a movable tracker-box located outside of said case and pivotally attached to said playing attachment. 75

3. The combination with a musical instrument having a keyboard, of a complete mechanical playing attachment hinged within the case of the instrument behind the lower front board thereof. 80

4. The combination with a musical instrument having a keyboard, of mechanical playing apparatus movably attached to the case of the instrument, a tracker-box arranged outside the case of the instrument, and supported by said playing apparatus, and pedals arranged outside the case and supported by the playing apparatus. 85

5. The combination with a keyboard instrument, of mechanical playing apparatus 90 movably arranged within the case of the instrument and a folding pedal board or frame supported from the framing of the playing apparatus and arranged outside of said case.

6. In an apparatus of the class described, 95 a mechanical playing apparatus adapted to be movably attached to the case of a musical instrument, a pivotally-supported tracker-box adapted to be arranged externally of said case, said tracker-box being connected to and supported by said playing apparatus, a folding pedal board or frame attached to and supported by said playing apparatus, and pedals hinged to said board or frame. 100

7. The combination with a keyed instrument, of pneumatically-operated mechanism for playing such instrument mechanically, said mechanism comprising pedal mechanism, a tracker-box, an expression-controller, a motor, motor-controller mechanism, a 110 motor-pressure regulator, and pneumatic-action devices, all mounted in relatively coactive positions on a suitable frame, and said frame being arranged within the case of the piano and hinged at one end so as to swing 115 outwardly from within the case, substantially as described. 115

8. The combination with a keyed instrument, of pneumatically-operated mechanical playing mechanism comprising pedals, bellows, pneumatics and a tracker-box connected together and supported by supporting means common to all, said supporting means being disposed within the case of the instrument and hinged at one end to said case, as 120 set forth. 125

9. The combination with a keyed instrument of a frame disposed within the case of the instrument and hinged at one end to said case, main bellows, pneumatic-motor mech- 130

anism, motor-controlling means, pneumatic-action devices, pneumatic-action-controlling devices, a tracker-box and a pedal-board carried by said frame.

5 10. The combination with a musical-instrument case and action, of mechanical playing apparatus, including tracker-box, motor, pneumatics, bellows, pedals and appurtenant parts, said playing apparatus being arranged

within the case of the musical instrument 10 and hinged thereto and bodily removable by the unjointing of the hinged connection.

In testimony whereof I affix my signature in the presence of two witnesses.

WILLIAM F. COOPER.
